US00D788803S

(12) **United States Design Patent** (10) Patent No.: **US D788,803 S**
(45) Date of Patent: ** Jun. 6, 2017

(54) **DISPLAY SCREEN OR PORTION THEREOF
WITH GRAPHICAL USER INTERFACE**

(71) Applicant: **Samsung Electronics Co., Ltd.**, Suwon-si, Gyeonggi-do (KR)

(72) Inventors: **Serrah Lim**, Bucheon-si (KR); **Neville Stanley Brody**, London (GB)

(73) Assignee: **S-PRINTING SOLUTION CO., LTD.**, Gyeonggi-Do (KR)

(**) Term: **15 Years**

(21) Appl. No.: **29/555,327**

(22) Filed: **Feb. 20, 2016**

(30) **Foreign Application Priority Data**

Aug. 20, 2015 (KR) 30-2015-0042072

(51) **LOC (10) Cl.** **14-04**

(52) **U.S. Cl.**

USPC **D14/486**

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The broken lines illustrate the display screen or portion thereof and form no part of the claimed design.
